SPRAY NOZZLE

Benjamin B. Fogler, Lexington, Mass., assignor to
 Arthur D. Little, Inc., Cambridge, Mass., a corporation of Massachusetts

Application October 25, 1945, Serial No. 624,553

8 Claims. (Cl. 299—143)

1

This invention relates to improvements in nozzles of the impingement-jet type.

Nozzles of the impingement-jet type characteristically consist of two opposing nozzles which produce a relatively flat tangential spray of liquid in a plane at right angles to the axis of the nozzles. These two nozzles are fed from a common source, which divides into two streams, one leading to each nozzle. In conventional construction, it is inevitable that the pipe carrying one of these streams shall intersect the trajectory of the spray of liquid at some point. As a result, the spray striking the pipe at the point of intersection coalesces and dribbles down the pipe, running off as drops, or as a stream, of unatomized liquid, and furthermore a coating of the solids (if any there be) in the liquid tends to build up on the pipe at and around the point of intersection.

According to the present invention there is provided an improved nozzle, or, more strictly speaking, nozzle assembly, of the impingement-jet type wherein these difficulties are entirely eliminated. In this improved nozzle assembly, the two opposed nozzles characteristic of the impingement-jet type of assembly are mounted upon a feed pipe which runs throughout the length of the assembly; this feed pipe is provided with openings leading into the chamber of that nozzle which is furthest from the feed source, so that the feed to such nozzle actually passes inside of the spray emerging tangentially from the orifice between the nozzles, and hence such feed pipe is not cut by this spray. The nozzle assembly of this invention is useful for the spraying or atomization of liquids, solutions, and suspensions generally, as in concentrating, spray-drying or spray-cooling, and liquid diffusing operations. It is intended in particular for operation at low to moderate pressures, e. g., up to about 200 p. s. i., although not exclusively limited thereto. As indicated above, the nozzle of this invention atomizes to a high degree and to uniform droplet size, especially because of the avoidance of any pipe or other fittings which cut the trajectory of the spray and thus serve to coalesce some of the atomized liquid.

This invention will now be described in detail with reference to the accompanying drawings which represent a typical form of the apparatus, without, however, intending to limit the invention strictly thereto, and wherein:

Fig. 1 represents a side elevation, partly diagrammatic, of one embodiment of the nozzle and the feed lines;

2

Fig. 2 represents a cross-section of the nozzle shown in Fig. 1; and taken along lines 2—2 of Fig. 3;

Fig. 3 represents a section taken along lines 3—3 of Fig. 2; and Fig. 4 represents a cross section of the upper part (feed end) of another embodiment of the nozzle and the feed lines.

Referring now to Figs. 1, 2 and 3, there are shown upper and lower nozzles 10 and 11, respectively, mounted concentrically on inlet pipe 12, so as to form two chambers—upper chamber 13 and lower chamber 14—of generally similar size and shape. Another inlet pipe 15 leads into the upper part of chamber 13. The inlet pipes 12 and 15 are fed from supply line 16, and are controlled by valves 17 and 18 respectively. Inlet pipe 12 extends completely through the nozzle assembly and projects at the opposite or lower end, where it is plugged in any convenient way as shown by numeral 20 to prevent passage of liquid, and is also threaded at the lower end 19 as shown. A nut is screwed over this threaded end 19 and into the recessed head 22 of lower nozzle 11, tightly against the packing material 23, to provide a leak-proof joint at opening 24 in the lower nozzle where inlet pipe 12 passes through it. Several holes 25 are provided in inlet pipe 12 to permit passage therefrom of liquid into lower chamber 14.

The upper and lower nozzles 10 and 11 are held concentrically with inlet pipe 12 by means of any convenient spacing devices, such as disks 26 and 27 provided with holes 28, as shown in more detail in Fig. 3. These disks may be held in position in any suitable way as by pins 29. The orifice openings 32, 33 of the upper and lower nozzles, respectively, which open into main orifice 30 are accordingly maintained in a uniform annular shape. Chambers 13 and 14 are of uniform annular cross-section in any plane at right angles to their axis, and this cross-section increases gradually in size from the orifice openings 32, 33 toward the vicinity of the ends of these chambers opposite said orifice openings.

In order to make sure that the assembly is leak-proof so that no liquid emerges except at the orifice 30, the joints and connections are packed, as already indicated in regard to the bottom end 19 of inlet pipe 12, or soldered—e. g. at the points of entrance of inlet pipes 12 and 15—or otherwise made tight.

In operation, the liquid to be sprayed is supplied from a source (not shown) to feed pipe 16, whence it divides and passes into inlet pipes 12 and 15. The amounts fed to inlet pipes 12 and

15 should be substantially equal, otherwise the spray 31 emerging from orifice 30 will be deflected from a substantially flat shape and assume a more or less conical shape. Equality in feed is attained by regulation of valves 17 and 18. Liquid entering inlet pipe 12 passes downwardly and into lower chamber 14 through holes 25, and thence upward through orifice opening 33 to main orifice 30, where it meets liquid which has entered inlet pipe 15 and passed downward through chamber 13 and orifice opening 32. The resulting two streams of liquid form the flat spray trajectory already referred to which is characteristic of impingement-jet nozzles.

The gap of orifice 30 may be adjusted by moving lower nozzle 11 toward or away from upper nozzle 10. This is readily accomplished by means of nut 21, since the lower nozzle 11 is slidably positioned on inlet pipe 12 at opening 24, while disk 37 is slidably fitted with respect to inlet pipe 12. So also is disk 26, for convenience in assembly.

The nozzle assembly may be held in position merely by inlet pipes 12 and 15, although for greater rigidity it may also be additionally secured or clamped by suitable means attached to the upper (inlet) end of nozzle 10.

Various modifications in the device described above may be made without departing from the scope of this invention as set forth in the appended claims. For example, the exact arrangement of the entrances of inlet pipes 12 and 15 to upper chamber 13 shown in the drawings may be varied, as long as they both enter that chamber without interfering with the spray. Thus, inlet pipe 12 might be led out of the side of the chamber 13 opposite inlet pipe 15, instead of at the end as shown; or pipes 12 and 15 might be arranged concentrically, though still keeping the two feeds separate as hereinabove described.

One such modification is shown in Fig. 4, wherein in place of the two separate feed pipes 12 and 15 of Figs. 1 and 2 a single feed pipe 34 is employed, which is provided with openings 35 leading into upper chamber 13 of upper nozzle 10. The rest of the nozzle assembly of Fig. 4 which is not shown is of the same form and arrangement as that shown in Figs. 1, 2 and 3, and operates in the same manner, feed being supplied to pipe 34 and passing in part, through openings 35, into upper chamber 13, and the balance passing, through openings 28, into lower chamber 14. The embodiment shown in Figs. 1, 2 and 3 is generally preferable from the standpoint of controllability of the feed to the two chambers (by use of valves 17 and 18), while that of Fig. 4 is somewhat more simple to manufacture.

I claim:

1. In a nozzle assembly of the class described, a feed pipe, a first and a second nozzle mounted in opposed position on and around said feed pipe and concentrically therewith, forming a first and a second chamber respectively about said feed pipe with an orifice between said chambers through which orifice said feed pipe passes, conduit means for carrying a supply of liquid feed into said nozzle assembly, all of said conduit means being located above the trajectory of the spray from said orifice, means for dividing the entire quantity of said feed into two substantially equal parts, means for conducting the flow of one of said two parts into said first chamber, and means for conducting the flow of the other of said two parts through said feed pipe and sub-

stantially throughout the length of said nozzle assembly and into said second chamber, said two means for conducting flow constituting the sole means for supplying feed to said first and second chambers and to said orifice, and said feed pipe constituting the sole support for and connection with said second nozzle and said second chamber.

2. In a nozzle assembly of the class described, a feed pipe, a first and a second nozzle mounted in opposed position on and around said feed pipe and concentrically therewith, forming a first and a second chamber respectively about said feed pipe with an orifice between said chambers through which orifice said feed pipe passes, an opening in said feed pipe leading into said first chamber, and another opening in said feed pipe leading into said second chamber, said feed pipe constituting the sole support for said second nozzle and said second chamber.

3. In a nozzle assembly of the class described, a feed pipe, a first and a second nozzle mounted in opposed position on and around said feed pipe and concentrically therewith, forming a first and a second chamber respectively about said feed pipe with an orifice between said chambers through which orifice said feed pipe passes, an opening in said feed pipe leading into said first chamber, another opening in said feed pipe leading into said second chamber, said pipe and said openings being arranged to deliver all of the feed to said chambers in substantially an equal amount to each chamber, and means for supplying feed to said feed pipe, said feed pipe constituting the sole support for said second nozzle and said second chamber.

4. In a nozzle assembly of the class described, a first inlet feed pipe, a first and a second nozzle mounted in opposed position on and around said first inlet feed pipe and concentrically therewith, forming a first and a second chamber respectively about said first pipe with an orifice between said chambers, a second inlet feed pipe communicating with said first chamber, means for supplying liquid feed to each of said pipes from a common source, and means for transmitting all of the feed from said first pipe into said second chamber, said first pipe constituting the sole support for said second nozzle and said second chamber.

5. In a nozzle assembly of the class described, first and second inlet feed pipes attached to a first nozzle, a second nozzle in opposed position to said first nozzle, said first nozzle and said second nozzle being mounted on and around said first pipe and concentrically therewith and forming a first and a second chamber respectively about said first pipe with an annular orifice between said chambers, common supply means for supplying liquid to said first and second pipes, and openings within said first pipe for transmitting all of the feed supplied to said first pipe to said second chamber, said second pipe being arranged to supply all of its feed to said first chamber, said first pipe constituting the sole support for said second nozzle and said second chamber.

6. In a nozzle assembly of the class described, a first inlet feed pipe, a first and a second nozzle mounted in opposed position on and around said first inlet feed pipe and concentrically therewith, forming a first and a second chamber respectively about said first pipe with an orifice between said chambers, a second inlet feed pipe communicating with said first chamber, means for supplying liquid feed to each of said pipes from a common

source and on the same side of said orifice, means for transmitting all of the feed from said first pipe into said second chamber, and means for controlling the supply of feed to each of said inlet pipes, said first pipe constituting the sole support for said second nozzle and said second chamber.

7. In a nozzle assembly of the class described, a first inlet feed pipe, a first and a second nozzle mounted in opposed position on and around said first inlet feed pipe and concentrically therewith, forming a first and a second chamber respectively about said first pipe with an orifice between said chambers, a second inlet feed pipe communicating with said first chamber, means for supplying liquid feed to each of said pipes from a common source and on the same side of said orifice, means for transmitting all of the feed from said first pipe into said second chamber, and means for adjusting said orifice comprising means for moving said second nozzle axially toward and away from said first nozzle, said first pipe constituting the sole support for said second nozzle and said second chamber.

8. In a nozzle assembly of the class described, a first inlet feed pipe, a first and a second nozzle mounted in opposed position on and around said first inlet feed pipe and concentrically therewith, forming a first and a second chamber respectively about said first pipe with an orifice between said chambers, a second inlet feed pipe communicating with said first chamber, means for supplying liquid feed to each of said pipes from a common source and on the same side of said orifice, means for transmitting all of the feed from said first pipe into said second chamber, means for adjusting said orifice comprising means for moving

said second nozzle axially toward and away from said first nozzle, spacer means for positioning the orifice openings of each of said nozzles concentric with said first pipe and uniformly annular, and means for controlling the supply of feed to each of said inlet pipes, said first pipe constituting the sole support for said second nozzle and said second chamber.
